CLAIM

The ornamental design for a smart patch device for medical diagnosis, as shown and described.

DESCRIPTION

FIG. 1.1 is a top view of a first embodiment of a smart patch device for medical diagnosis; and
FIG. 2.1 is a top view of a second embodiment of the smart patch device for medical diagnosis.

(Continued)

The broken lines in the drawings depict portions of the smart patch device for medical diagnosis that form no part of the claimed design.

1 Claim, 2 Drawing Sheets
